UNITED STATES PATENT OFFICE.

PEDER ANDERSEN FISKER, OF COPENHAGEN, DENMARK.

AIR-PUMP

1,034,894.

Specification of Letters Patent.

Patented Aug. 6, 1912.

Application filed December 31, 1910. Serial No. 600,368.

To all whom it may concern:

Be it known that I, PEDER ANDERSEN FISKER, of Copenhagen, Denmark, have invented a new and useful Improvement in 5 Air-Pumps, of which the following is a full, clear, and exact description.

My invention relates to improvements in air pumps for which motive power is preferably supplied by an electric motor, and 10 which though they may be used for any desired purpose, are more especially adapted for use in a vacuum cleaner, so called, which requires a suction device for the removal of dust and dirt from carpets, rugs, 15 floors etc.

The object of my invention is to provide an air pump which is a simple and powerful suction device, and to this end I provide a series of two or more suction wheels operated 20 on a common shaft and so arranged that the air as drawn in by one wheel is thrown by means of the intervening plates toward the center of the wheel next to it. In this way I provide a device which is very 25 compact in form, simple in construction, but in which the power of each suction wheel is fully utilized, and which by reason of the form of the intervening plates between the suction wheels, is practically 30 noiseless in operation.

Reference is to be had to the accompanying drawings forming a part of this specification, in which similar reference characters indicate corresponding parts in all the 35 views.

Figure 1 is an elevation partly in section, of the apparatus embodying my invention. Fig. 2 is a sectional view of a detail on the line A—B of Fig. 1, and Fig. 3 is a sectional 40 view of a detail on the line C—D of Fig. 1.

Means for operating the apparatus comprising my invention may be supplied in any desired way. I have indicated in the drawings a simple and convenient way 45 which is represented by the motor 1, one bearing of the motor being shown in the drawing as supported in the casing 2. The entire apparatus is provided on the top with a handle 3. The other bearing of the motor 50 is supported by the cup shaped extension or casing 4 which surrounds the outer end of the shaft 5. This part of the shaft 5 carries one or more suction wheels 6. In the drawings but two of these wheels are shown, 55 but it will be understood that if desired three or four or any number may be used.

The suction wheels 6 are rigidly supported on the shaft 5 and spaced apart in any desired way as by a piece of tube 7. These suction wheels themselves are in the form 60 of solid circular disks, and are provided on their lower surfaces with radially arranged vanes. These vanes are so shaped that they taper slightly toward the periphery of the disk. Between the wheels 6—6 I provide 65 two plates 9 and 10 which are supported on their outer edges by the casing 4 in such a way that along their circumference they are held tightly against the casing or cylinder 4. The upper plate 9 is provided with 70 a hole at its center somewhat larger than the shaft of the motor. The other plate 10 is provided with a series of perforations near its periphery and is adapted to fit closely around the shaft of the motor in 75 the center. This plate 10 is further provided on its upper surface with ribs 11 inwardly turned toward its center, and of sufficient height to space the plates 9 and 10 apart. The lower part of the casing or 80 cylinder 4 is closed by the plate 12 which has an opening in the middle. This plate 12 carries near its outer circumference a flange 13 which fits inside the casing 4 and also has a downwardly extending flange to 85 fit and hold the apparatus on a bucket or receptacle 14. Between the bucket 14 and the plate 12 is provided packing 20, and the parts are clamped together by means of the hinged hooks 23. At the top of the 90 casing 4 I provide outlet openings 22. In the lower part of the bucket is shown an opening 21 which may be connected in the ordinary manner with a hose provided with a suitable mouth piece such as is used in a 95 vacuum cleaner. I have not indicated in the drawings leading-in wires for the motor, but it will be understood that such wires and a suitable controller may be provided.

When the suction wheels are rotated by 100 the motor a partial vacuum will be caused in the bucket 4 by the air being drawn up by the lower wheel 6 and forced against the inner surface of the casing 4, up through the perforations 24 in the plate 10. The air 105 then is forced by means of the ribs 11 toward the center of the plate 9 and is then drawn up by the upper wheel 6 and forced out of the apparatus through the openings 22. In this way the full suction power of 110 the wheels 6—6 is utilized, and by providing the intervening plates, one of which is

perforated near its periphery and has the inwardly turned vanes on its upper surface, the air pump is comparatively noiseless in operation.

5 I claim:—

An air pump comprising a receptacle having an air opening therein, a casing seated in the receptacle and provided with air openings in the upper part thereof, a 10 vertically arranged shaft in the casing, suction wheels spaced apart on the said shaft, each wheel comprising a plate with ribs or wings on the under side thereof, and stationary plates between the suction wheels 15 and beneath the lowest suction wheel, the edge of each of said plates being supported

by and in close contact with the wall of the casing, said plates being alternately provided with an opening near the center and perforations near the peripheral edge, the 20 plates having perforations near the edge having curved ribs on one surface extending from the periphery to a point near the center.

In testimony whereof, I have signed my 25 name to this specification in the presence of two subscribing witnesses.

PEDER ANDERSEN FISKER.
